UNITED STATES PATENT OFFICE

2,071,794

RAILWAY CAR TRUCK

Joel Hektner, Canton, Ohio, assignor to The Timken Roller Bearing Company, Canton, Ohio, a corporation of Ohio

Original application September 3, 1935, Serial No. 38,866. Divided and this application July 10, 1936, Serial No. 89,924

3 Claims. (Cl. 105—223)

This application is a division of my application Serial No. 38,866 filed September 3, 1935 for Railway car truck.

The invention relates to trucks for railway cars whose axles are mounted in antifriction bearings and it has for its principal object to relieve the bearings of such an axle of torsional strains due to individual wheel or axle movements relative to other parts of the truck. The invention consists principally in mounting the bearing housing of such an axle or frame in such a way as to permit such housing to have a pivotal movement about an axis transverse to the axle and also about a vertical axis, such double pivoting of the bearing housing permitting self-aligning movement of the bearings and thus relieving them of torsional strains. The invention further consists in the railway car truck and in the parts and combinations and arrangements of parts hereinafter described and claimed.

In the accompanying drawing.

Fig. 1 is a partial vertical sectional view of a railway car axle and the adjacent portion of a car truck embodying my invention,

Fig. 2 is a transverse vertical sectional view on the line 2—2 in Fig. 1, looking in the direction of the arrows; and

Fig. 3 is a sectional view on the line 3—3 in Fig. 2, looking in the direction of the arrows.

In the drawing is shown a truck side frame 1 of common construction provided with an end portion that has spaced perforated bosses 2 on its under side to receive a pin 3 that is disposed transversely of the axle 4. Mounted on said pin 3 is a pivot block 5 that has a central stem portion 6 of cylindrical configuration oscillatable in a concave seat 7 provided on the under side of the end portion of said side frame between said bosses 2 and which has projecting bottom flange portions 8 that are received in slots 9 formed by upstanding lugs 10 on the bearing housing 11, said lugs having flanged portions 12 overlapping the sides of said pivot block flanges 8. Said flanges 8 are convexly curved from end to end, whereby said bearing housing is permitted swinging movement on said flanges 8 of said pivot block 5.

Extending into the bearing housing 11 is the end portion of the axle 4 of a railway car or the like, on which are mounted spaced tapered roller bearings. The cones 13 or inner bearing members are spaced apart by a sleeve 14 mounted on the axle. The bearing cones 13 are arranged with their large ends disposed inwardly and

the innermost bearing cone 13 is mounted against a closure and abutment ring 15 which is seated against a shoulder 16 on the axle. Bearing rollers 17 are mounted on said cones 13 and the cups 18 or outer bearing members are mounted in said housing 11, whose outer end is closed by a cap 19 that is secured to the housing by screws 20 and that has an inwardly extending sleeve portion 21 that abuts against the outermost bearing cup 18. The innermost end of the bearing housing 11 is closed by a ring 22 that is secured to the housing by screws 23 and has a sleeve portion 24 extending inwardly into the bearing housing, abutting against the innermost bearing cup 18 to hold it in position. The drawing shows only one end portion of one axle, it being understood that the other end portion of the other axle will be of similar construction and that the truck side frame member may be of any well-known type. While the bearing arrangement just described is a preferred arrangement, it is understood that the invention is not limited to any specific bearing arrangement, but is concerned with the pivotal mounting of the bearing housing.

The above described mounting of the bearing housing permits swinging movement of the bearings and housing about an axis transverse to the axle and also about a vertical axis. Thus self-aligning movement of the bearings and housing is permitted while maintaining tightness of fit of the parts under all conditions. Obviously, numerous changes might be made, particularly in the truck side frame construction and in the bearing arrangement, without departing from the invention and I do not wish to be limited to the precise construction shown.

What I claim is:

1. A car truck comprising a frame member, an axle, a bearing housing receiving said axle, antifriction bearings between said axle and said housing, the top of said housing having spaced overhanging lugs, a pivot block having flanges fitting beneath said lugs, said flanges being convexly curved endwise and a pivot pin supporting said pivot block, said pin being secured to said frame and extending transversely of the axle.

2. A car truck comprising a frame member, an axle, a bearing housing receiving said axle, antifriction bearings between said axle and said housing, said frame having spaced perforated bosses disposed transversely of said axle, the top of said housing having spaced overhanging lugs, a pivot block having a portion disposed between said bosses and having flanges fitting beneath

said lugs, said flanges being convexly curved endwise and a pivot pin extending through said bosses and said pivot block.

3. A car truck comprising a frame member, an axle, a bearing housing receiving said axle, anti-friction bearings between said axle and said housing, said frame having a concave seat extending transversely of the axle and spaced perforated bosses at the ends of said seat, the top

of said housing having spaced overhanging lugs, a pivot block having a portion disposed between said bosses and convexly curved on its top to fit said concave seat and said block having flanges fitting beneath said lugs, said flanges being convexly curved endwise and a pivot pin extending into said boss perforations and supporting said pivot block. 5

JOEL HEKTNER.
